Des. 175,452
Patented Aug. 30, 1955

175,452

CABINET HANDLE OR THE LIKE

Vytant P. Aleks, Rockford, Ill., assignor to National Lock Company, Rockford, Ill., a corporation of Delaware

Application March 7, 1955, Serial No. 34,889

Term of patent 14 years

(Cl. D10—8)

Fig. 1.

Fig. 2.

Fig. 3.

Fig. 4.

Fig. 5.

Fig. 2 is a view in front elevation thereof;

Fig. 3 is a rear elevation thereof;

Fig. 4 is a view in elevation of one end of the cabinet handle; and

Fig. 5 is a view in elevation of the other end thereof.

I claim:

The ornamental design for a cabinet handle or the like, substantially as shown.
